(57) **CLAIM**

The ornamental design for a display screen or portion thereof with graphical user interface, as shown and described.

DESCRIPTION

FIG. 1 is a display screen or portion thereof with graphical user interface showing my new design;

FIG. 2 is the claimed portion of FIG. 1, shown within a different broken line environment;

FIG. 3 is the claimed portion of FIG. 1, shown enlarged and within a different broken line environment; and,

FIG. 4 is the claimed portion of FIG. 1, shown enlarged and within a different broken line environment.

The broken lines and text indicate unclaimed portions of the article and form no part of the claimed design.
